UNITED STATES PATENT OFFICE.

CHARLES G. SMITH, OF MEDFORD, MASSACHUSETTS, ASSIGNOR, BY MESNE ASSIGNMENTS, TO RAYTHEON MANUFACTURING COMPANY, OF CAMBRIDGE, MASSACHUSETTS, A CORPORATION OF MASSACHUSETTS.

PRODUCTION OF ELECTRICAL VARIATIONS.

Application filed October 8, 1920. Serial No. 415,537.

The present invention relates to a method and apparatus for producing energy variations in electrical circuits.

According to a copending Patent No. 5 1,545,207, granted July 7, 1925, a new form of insulating gap embodying a gaseous medium has been disclosed. In this apparatus the use of properly designed and located electrodes immersed in a gas affords paths 10 for the passage of electrons through the gas too short to permit substantial ionization to take place. As disclosed in said patent, this result is secured by spacing the active surfaces of the electrodes at different potentials a relatively short distance apart, the space separating these surfaces being of the order of magnitude of the mean free path of the electrons to avoid collision of electrons, and atoms and consequent electric discharge. 15 In addition all paths through the insulating dielectric which are subject to a potential gradient are made sufficiently long to prevent breakdown.

I have discovered that it is possible to vary 20 the path of travel of the electrons in a manner to render an otherwise insulating gap conducting and to, in addition, vary the conductivity of the gap as desired. In the best form of the invention now known, the operation 25 of the gap may be controlled by the interposition of a fluctuating magnetic field in the space between the electrodes which may distort the path of travel of the electrons sufficiently to make the gap alternately 30 conducting and nonconducting.

The inherent capacity of the gap to vary in conductivity in accordance with the variations in a magnetic field permits the apparatus to be utilized as a relay or amplifier 40 when provided with an output circuit containing the electrodes and an input circuit arranged to vary the magnetic field between the electrodes, the fluctuations of energy in the output circuit being caused by the fluctuating magnetic field. If the input circuit be 45 connected with the output circuit in a manner to cause the fluctuations of the magnetic field to be derived from the output circuit then the apparatus may be employed as an 50 oscillator or generator of alternating currents.

One feature of the present invention accordingly consists in the embodiment of two electrodes immersed in a gas and having

their active surfaces located in sufficiently 55 close proximity to normally prevent electric discharge through the gas at a given potential with means for varying the normal path of travel of the electrons through the gas to accordingly vary the conductivity of 60 the apparatus.

A further feature of the invention consists in the use of a fluctuating magnetic field in the space between the electrodes to vary 65 the conductivity of the space and cause the excitation of alternating current either in a circuit including the electrodes directly or in a circuit inductively or otherwise coupled to the above circuit.

In a simple and efficient mechanical embodiment of the invention two electrode tubes of different diameters are located in concentric relation with all portions of their active surfaces at different potentials located 70 in close proximity. These tubes are immersed in a gas which is subjected to a fluctuating magnetic field created in any suitable manner. This magnetic field may fluctuate in a manner to alternately render the tube conducting or nonconducting or in a manner to 75 vary the conductivity of the tube without causing it to become totally nonconducting to the impressed voltage.

In the accompanying drawings illustrating 80 one embodiment of the invention Fig. 1 represents a section in elevation of a tube embodying the principles of the invention; Fig. 2 is diagrammatic view of a circuit arrangement in which the input circuit, including 85 the means for creating the magnetic field, derives its energy from the output circuit, including the electrodes; Fig. 3 is a slightly modified form of Fig. 1 illustrating the use of a permanent magnet for the creation of a 90 constant magnetic field with a coil for imposing an additional fluctuating increment of magnetic field; and Fig. 4 is a diagrammatic view illustrating a suitable circuit arrangement when using the tube as an amplifier.

According to the illustrated embodiment 95 of the invention, two electrode tubes 10 and 12 are enclosed within a containing receptacle 14 which is filled with gas at a constant pressure. The containing vessel may 100 be of glass or other insulating material as shown, and the electrode tubes are conveniently supported at their lower ends by insu-

lating supports 16 and 18, forming an integral part of the base of the vessel. The inner and outer tubes are respectively connected with leads 20 and 22 which pass out of the containing receptacle in such a manner that there is no possibility for short circuit through the insulating dielectric. The electrode tubes which are under a potential difference are so designed and located with respect to one another that there is normally no gaseous conduction between them. This insulating property of the tubes is due to the fact, as previously explained, that the distance separating the surfaces of the tubes under a potential difference is of the order of magnitude of the normal mean free path of the electrons.

The region separating the active surfaces of the tubes is subjected to a fluctuating magnetic field to vary the conductivity of the tube as a whole. This may be conveniently accomplished by the provision of an electro-magnet 24 designed to create a constant field and additional coils 26 located in circuit with a varying source of potential to correspondingly vary the intensity of the magnetic field. By proper design of the coils and with a suitable circuit arrangement, variations of the field may be designed to vary the conductivity of the tube at will. By providing an input circuit 25 including a source of alternating potential 27 connected with the coil 26, as indicated in Fig. 4, the conductivity of the tube is varied upon closing the switch 28. If, in addition, an output circuit 35 is provided having a source of potential 36 and including the electrodes 10 and 12, the variations in the conductivity of the tube thus produced will act upon the output circuit in a corresponding manner and cause the tube to operate as a relay or amplifier, the fluctuations of energy thus produced being utilized by any desired form of circuit.

It is possible that by connecting an input circuit 32 with an output circuit 29, as shown in Fig. 2, so that the fluctuations in the magnetic field are excited through back connection from the output circuit, the tube may be caused to act as a generator of oscillatory currents.

It will be obvious to those skilled in the art that the constant magnetic field may be created either through an electro-magnetic coil, as shown in Fig. 1, or by a permanent magnet 40 of suitable form, as indicated in Fig. 3. If it is desired to vary the intensity of the field produced by this permanent magnet, an armature 41 may be adjustably connected with the opposite poles of the magnet through adjusting members 44 and 45 in such a manner that by moving the armature toward and from the magnet the desired adjustment of field strength may be obtained.

When the tube is conducting, the bombardment of the surfaces of the electrodes may give rise to some disintegration of the latter and while the loss of metal in itself is not of importance the spattering of the metal upon the insulating dielectric may eventually cause short circuits and consequent breakdown of the tube. To avoid possibility of such an occurrence, it is desirable to localize the region of discharge between the surfaces of the electrodes and this is accomplished in the illustrated embodiment of the invention by localizing the magnetic field, as will be observed from an inspection of Figs. 1 and 2 of the drawings. Owing to the construction and arrangement of the magnets with respect to the tube, the field is localized at a distance from the insulating supports in such a manner that the discharge between the electrodes occurs well away from the supports.

It is important for the successful operation of apparatus of this character that the gas pressure within the receptacle shall be maintained substantially constant. If it were necessary to maintain a perfect vacuum or a nearly perfect vacuum, as in the case of the usual thermionic tubes, it would be necessary for the enclosing vessel to be carefully constructed of material impervious to the leakage of gas therethrough, but as the present apparatus will operate successfully with a considerable gas pressure, especially when employing some form of inert gas, it is feasible to maintain a substantially constant pressure even when using metal or other enclosing receptacles through which intolerable leakage would ordinarily occur if operating with a substantially perfect vacuum. To insure maintenance of the best operating gas pressure it is preferable to completely remove from the tube all active gases that would ordinarily combine with the electrode material and condense on the walls of the enclosing vessel and fill the tube with an inert gas.

The insulating ring 16 serves the two-fold purpose of supporting the outer electrode and localizing the electrical phenomena accompanying the gaseous discharge within the hollow electrode. By extending the insulation 16 longitudinally of the surface of the inner electrode in spaced relation thereto, from the open end of the outer electrode to the end of the inner electrode, at a distance substantially confined to the mean free path of the electrons in the gas (this spacing being approximately the same as that between the two electrodes) the normal tendency of the discharge to seek the junction between the smaller electrode and the insulation is minimized.

Referring to Figure 3 the hollow cathode 10 has an opening in its lower end facing

the reentrant stem 18 which supports the anode 12, and the insulation material 16 bridges the space between the hollow cathode and the conductor 20, which conducts current to the anode 12, whereby the aforesaid opening is closed.

In a generic sense, the term "hollow cathode" includes a cathode whose active surface only partially surrounds a gaseous medium so that the medium immediately adjacent the active surface is more or less pocketed or confined.

I claim—

1. An electrical apparatus comprising electrodes immersed in a gas and located in sufficiently close proximity to each other to normally prevent gaseous conduction and means for creating a fluctuating magnetic field which extends transversely of lines 20 bridging the space between the electrodes to vary the conductivity of the gaseous medium in accordance with the fluctuations in the magnetic field.

2. An electrical apparatus comprising a gas-filled receptacle, electrodes supported within the receptacle at different potentials and having their surfaces separated a distance approximating the normal mean free path of electrons in the gas to normally prevent gaseous conduction, and means for producing a magnetic field of varying intensity 30 transversely in the space between the electrodes to render the conductivity of the gap variable in accordance with the fluctuations 35 in the field.

3. An electrical apparatus comprising a gas-filled receptacle, electrodes mounted within the receptacle, supporting means for holding the electrodes in spaced relation with 40 their surfaces positioned in close proximity to each other to normally prevent gaseous conduction, and means for creating a fluctuating magnetic field transversely in the space between the electrodes to permit fluctuating electric discharge through this space 45 in response to potential difference between electrodes.

4. An electrical circuit including two spaced electrodes immersed in a gas and having their surfaces at different potentials separated a distance approximating the normal mean free path of electrons in the gas to normally prevent gaseous conduction, means for creating a magnetic field transversely in the space separating the electrodes and means for impressing another variable field upon the magnetic field thus created periodically to permit conduction between the electrodes in response to said difference 55 in potential.

5. An electrical apparatus comprising a gas-filled receptacle, spaced electrodes enclosed within the receptacle, a circuit including the electrodes and gas in which they are immersed, the electrodes having their

surfaces located in close proximity to each other to normally prevent electric discharge through the gas, and means to cause pulsating conduction through the gas.

6. An electrical apparatus comprising a gas-filled receptacle, concentric electrode tubes enclosed within the receptacle, means for supporting and locating the tubes, the tubes being designed and arranged to normally prevent gaseous conduction, and means 75 for creating a fluctuating magnetic field through a portion of the gas removed from the supporting means periodically to permit gaseous conduction between corresponding portions of the electrode tubes in response 80 to potential differences between electrodes.

7. An electrical apparatus comprising a gas-filled receptacle, concentric electrode tubes enclosed within the receptacle, means for supporting and locating the tubes in a 85 manner to normally prevent gaseous conduction, and variable means to permit pulsating gaseous conduction to take place between a restricted portion of the tubes in response 90 to potential difference between the electrodes.

8. An electrical apparatus comprising two electrodes immersed in a gas and located in sufficiently close proximity to normally prevent gaseous conduction, a circuit connected 95 to the electrodes and including a source of potential and a second circuit designed to create a magnetic field in the region separating the surfaces of the electrodes and connected to the first mentioned circuit in a 100 manner to be influenced thereby.

9. An electrical apparatus comprising a gas filled receptacle, electrodes enclosed in the receptacle and having active opposing surfaces separated a distance comparable to the mean free path of electrons in the gas, path lengthening means for increasing the paths of electrons passing between the electrodes to cause gaseous ionization and conduction, and means for periodically varying 105 the path lengthening means to cause similar variations in the conductivity of the gas.

10. An electrical apparatus comprising a gas filled envelope, cooperating electrodes received within the envelope and having their opposed surfaces spaced apart a distance approximating the order of magnitude of the mean free path of electrons in the gas, an electric circuit including the electrodes, and means including another electric circuit 115 for varying the conductivity of the gaseous space separating the electrodes.

11. An electrical apparatus comprising a gas filled envelope, cooperating electrodes received within the envelope and having their opposing surfaces spaced in sufficiently close proximity to prevent gaseous conduction therebetween, an electric circuit including the electrodes, and means for creating a fluctuating magnetic field transversely in the 125 130

- gaseous space separating the surfaces of the electrodes.
12. An electrical apparatus comprising a gas filled receptacle, a plurality of electrodes in the receptacle having surfaces spaced a distance comparable to the mean free path of electrons in the gas, path lengthening means for deflecting electrons between the electrodes to lengthen their paths and permit conduction between the electrodes, and a circuit connected with the path lengthening means and adapted to have oscillations impressed thereon to vary the conductivity of the gaseous region in accordance with such oscillations.
13. A gaseous conduction device comprising a hollow electrode closed except for an opening in one end, a cooperating electrode presented to the interior surface of the hollow electrode through said opening, means for producing gaseous conduction between said electrodes, and means responsive to said gaseous conduction for impressing a variable magnetic field upon the space between the electrodes, thereby to vary the conduction path between electrodes.
14. A gaseous conduction device comprising a hollow electrode closed except for an opening in one end, another electrode presented to the interior of the hollow electrode through said opening, and variable magnetic means for varying the state of ionization of the gas inside the hollow electrode, thereby to control the current flow between the two electrodes.
15. The method of producing pulsating gaseous conduction between two electrodes spaced sufficiently close normally to prevent conduction therebetween, which comprises concomitantly impressing electric and magnetic fields upon the space between the electrodes and recurrently varying the state of ionization of the gas by varying the magnetic field, thereby to render the path between the two electrodes alternately conducting and relatively non-conducting.
16. A gaseous conduction device comprising a tube having a reentrant stem at one end, a hollow cathode in the tube with an opening therein facing said stem, an anode surface supported by said stem and presented to the interior of the hollow cathode, a conductor for conducting current to the anode surface, and insulation material bridging the space between the hollow cathode and conductor, whereby the opening is closed.
17. A gaseous conduction device comprising a tube having a reentrant stem at one end, a hollow cathode in the tube with an opening therein facing said stem, an anode surface supported by said stem within the hollow cathode, a conductor extending through said opening for conducting current to the anode surface, and insulation material bridging the space between the hollow cathode and conductor.
18. An electrical discharge device comprising electrodes having discharge surfaces presented to each other across an intervening gas space, and insulating material extending along one of said surfaces adjacent said space in spaced relation to the surface, the gap between the surface and the insulation being substantially confined to the mean free path of electrons in the gas.
19. An electrical discharge device comprising electrodes having discharge surfaces presented to each other across an intervening gas space, and a shield extending along one of said surfaces adjacent said space in spaced relation to the surface, the gap between the surface and the shield being substantially confined to the mean free path of electrons in the gas.
20. An electrical discharge device comprising electrodes presented to each other across an intervening gas space, one electrode being smaller than the other, and insulation surrounding the smaller electrode adjacent said space in spaced relation to its outer surface, the gap between said surface and the insulation being substantially confined to the mean free path of electrons in the gas.
21. A gaseous conduction device comprising a hollow electrode having an opening therein, a smaller electrode extending into said opening, and insulation surrounding the smaller electrode in spaced relation thereto adjacent said opening, the gap between said smaller electrode and insulation being substantially confined to the mean free path of electrons in the gas.
22. A gaseous conduction device comprising a tubular electrode having an open end, a cylindrical conductor extending into said open end and terminating in an electrode surface within the hollow electrode, and an insulating ring surrounding said conductor in spaced relation thereto adjacent said opening, the gap between the conductor and ring being substantially confined to the mean free path of electrons in the gas.
23. A gaseous conduction device comprising a receptacle having a reentrant stem and containing two electrodes, an insulating ring surrounding said stem with a gap therebetween comparable to the mean free path of electrons in the gas, a lead to one electrode extending through said stem and the other electrode being mounted on said ring.
24. A gaseous conduction device comprising a receptacle having a reentrant stem, an electrode mounted on said stem, an insulation ring surrounding said stem with a gap therebetween comparable to the mean free path of electrons in the gas, said ring being integrally joined to said stem at the

end of the ring nearest the base of the stem, and another electrode mounted on said ring.

25. A gaseous conduction device comprising a glass receptacle having a reentrant stem, a glass ring integrally joined to the stem at the end of the ring nearest the base of the stem and extending along the periphery of the stem in close juxtaposition thereto, an electrode conductor extending through the stem, and an electrode mounted on the ring.

CHARLES G. SMITH.
